UNITED STATES PATENT OFFICE.

CHARLES DIENER, OF NEW YORK, N.Y.

SAW-SET.

SPECIFICATION forming part of Letters Patent No. 793,997, dated July 4, 1905.

Application filed January 30, 1905. Serial No. 243,250.

To all whom it may concern:

Be it known that I, CHARLES DIENER, a citizen of the United States, and a resident of the city of New York, borough of Brooklyn, 5 in the county of Kings and State of New York, have invented a new and Improved Saw-Set, of which the following is a full, clear, and exact description.

The purpose of the invention is to provide 10 a simple, economic, and effective saw-set adapted for use in connection with any character of saw, one which can be conveniently operated and which will have a hammer action, enabling the teeth of the saw to be set 15 as accurately and readily outside of the shop as at a bench within the shop.

A further purpose of the invention is to provide a light tool which can be readily carried in a tool chest or bag and which is always 20 ready for use, having no parts liable to become separated and lost.

The invention consists in the novel construction and combination of the several parts, as will be hereinafter fully set forth, 25 and pointed out in the claims.

Reference is to be had to the accompanying drawings, forming a part of this specification, in which similar characters of reference indicate corresponding parts in all the figures.

Figure 1 is a plan view of the improved tool. Fig. 2 is a longitudinal section taken practically on the line 2-2 of Fig. 1. Fig. 3 is a side elevation of the device, illustrating 30 its construction for heavy work; and Fig. 4 is a plan view of the device shown in Fig. 3.

The head A of the tool is of skeleton formation, being preferably somewhat oval. The ends 10, however, are given more or less of 40 an upward curve, and said head is deepest at its front and rear side portions 11 and 12, as is shown in Fig. 2. A vertical recess 13 is made in the inner face of the front central portion of the head, adapted to receive a removable anvil-block 14, whose lower end is downwardly and outwardly beveled from its inner face, as is shown at 15 in Fig. 2. The anvil-block is held in place by attaching thereto a threaded stem 17, which passes out

through an opening 18 in the front portion 50 11 of the head, having a thumb-nut 19 and washer applied to its projecting end, as is also shown in Fig. 2.

A tubular handle 20 is attached to or is made integral with the rear central portion 55 12 of the head A, being separated by a partition 21 into a forward chamber 22 and a longer rear chamber 23. The chamber 22 is open at the top; but the rear chamber 23 is practically closed, except that an opening 24 60 is produced at its outer end and a longitudinal slot 25 is made in its upper face. In preferably the right-hand wall of the said slot 25 one or more recesses, preferably two, 65 26 and 27, are formed.

An upwardly and rearwardly inclined jaw 28 is introduced into the head A from the bottom, having a V-slot 29 in its upper edge, and when the jaw 28 is in position the slot 29 is opposite the straight inner face of the anvil-block 14. The jaw 28, which serves as a guide for the blade 30 of the saw, is adjustably held in position by forming a rearwardly-extending link 31 at its bottom, through which link a set-screw 32 is passed 70 75 into the handle.

In the rear side portion 12 of the head A a rectangular opening 33 is produced, which is in longitudinal alignment with the anvil-block 14, and a corresponding opening 34 is 80 produced in the partition 21, which latter opening is by preference circular. A setting-bar B has sliding movement in the two openings 33 and 34, the forward portion 35 of the said setting-bar being preferably rectangular 85 in cross-section, so that it cannot turn in the opening 33, and when the setting-bar is in position its inner end has free play in the opening 34 in the partition 21, and its forward end has free movement in the opening 90 33 in the head, and the striking or outer end of the setting-bar will pass through the slot in the jaw 28 and will be in position when forced forward to strike against the anvil-block 14 or the tooth of a saw held between 95 the slotted portion of the jaw 28 and the said anvil-block, as is illustrated in Fig. 2. The setting-bar is normally held away from the

anvil-block 14 by means of a spring 36, located in the chamber 22 of the handle, which spring is coiled around the said setting-bar and has bearing against the head at one end 5 and against a pin 37 at its opposite end, which pin is passed through the setting-bar. The setting-bar is adapted to be struck at its rear end by a hammer 38, which hammer is also in the form of a bar and is located in the 10 longer chamber 23 of the handle. The outer end of the hammer 38 extends out through the end opening 24 in the handle.

The hammer 38 is provided with an attached post 39, and this post extends out 15 through the slot 25 in the top of the handle and is capable of being carried from end to end of the said slot and also of being made to enter either of the recesses 26 and 27. A spring 40 is coiled around the hammer 38, 20 having bearing against the post or stud 39 at its forward end and against the rear end wall of the said chamber 23 at its opposite end, as is also shown in Fig. 2. Normally the forward end of the hammer 38 is in engagement with the rear end of the setting-bar B. After the saw has been placed between the 25 jaw 28 and the anvil-block with a tooth opposite the slot 29 in the jaw, the jaw is adjusted forward and locked so as to hold the saw in its adjusted position. The hammer 30 38 is then drawn back by carrying the stud 39 to the rear portion of the slot 25, and until the setting blow is to be given the hammer can be held in its rear or striking position by carrying the stud 39 into either the recess 26 35 or the recess 27, according to the force of the blow required. As soon as the post 39 is placed in position to slide in the slot 25 and is released, the spring 40, which had been 40 placed under tension, will force the hammer forwardly and cause it to strike more or less forcibly against the rear end of the setting-bar, driving the forward end of the latter with more or less force in contact with the 45 tooth to be set.

I desire it to be understood that the spring 40 may be more or less strong, and if said spring is exceptionally strong I contemplate the use of a lever suitably applied for setting 50 the hammer or placing it under tension, the said lever being a substitute for the post 39. Such a construction I have shown in Figs. 3 and 4, wherein it will be observed that the slot 25 is omitted from the handle 20, and in 55 its stead a straight longitudinal slot 41 is produced in one side, and the spring 40 of the hammer 38 does not bear against a vertical pin 39, but against a horizontal pin 46, which extends out through the slot 41, being 60 provided with a friction-roller 47 at its outer end. At each side of the outer end portion of the handle 20 parallel and vertically-disposed bearings 42 are produced, and a short shaft 43 is journaled in the upper portions

of said bearings. At one end of the shaft 43 65 a gear-wheel 44 is secured, and a lever 45 is attached to the gear, whereby the gear may be turned by hand. The friction-roller 47 has bearing against the convexed rear edge of a segmental bar 48, located at the opposite 70 side of the handle to that bearing the gear 44, and the lower end of the segmental bar 48 is secured to a shaft 49, journaled in bearings 50 at the under side of the handle 20. A pinion 51 is fastened at the opposite end of 75 the shaft 49, meshing with the gear-wheel 44. Thus in operation by moving the hand-lever 45 in one direction by means of the gear 44 and pinion 51 the segmental bar 48 is rocked toward the inner end of the handle 20, 80 and by constant engagement with the friction-roller 47 the said bar 48 at such time forces the hammer 38 in the same direction, placing the spring 40 under compression, and as soon as the hand-lever 45 is released the 85 said spring 40 acts to carry the hammer to its normal position and to a forcible contact with the setting-bar B.

Having thus described my invention, I claim as new and desire to secure by Letters 90 Patent—

1. In a saw-set, a head and a handle therefor, the head being provided with an anvil and with an adjustable jaw, a setting-bar having end movement partially in the head 95 and partially in the handle, the end of the setting-bar in the head being opposite the anvil, a hammer having end movement in the handle, means for locking the hammer temporarily in a rear or striking position, and 100 means for forcibly carrying the hammer to contact with the setting-bar when the hammer is carried from its striking position.

2. A saw-set, comprising a head having an 105 anvil-block and a slotted jaw, a tubular handle forming a portion of the head, a spring-controlled setting-bar having end movement in the handle and in the head, the end of the bar in the head being opposite the said anvil-block and the slot in the jaw, normally passing 110 through the latter, a spring-controlled hammer having end movement in the handle, and means for locking the hammer in temporary position under the tension of the 115 spring.

3. A saw-set, comprising a skeleton head, a tubular handle forming a portion of the head, an anvil-block located in the head, a slotted jaw located opposite the anvil-block, a spring-controlled setting-bar having 120 guided end movement partially in the handle and partially in the head, the end of the setting-bar in the head being opposite the slot in the jaw and opposite the anvil, the handle being provided at the rear of the setting-bar 125 with a longitudinal slot having recesses in one of its walls, a hammer having end movement in the said handle, one end of said

hammer being normally in engagement with the rear end of the setting-bar, a post extending from the hammer through the slot in the handle, and a spring coiled around said hammer between the post and the end of the handle.

4. A saw-set, comprising a head, a tubular handle secured to the head and having a longitudinal slot, an anvil carried by the head, a jaw also carried by the head, opposite the anvil, a spring-pressed setting-bar having end movement in the head and handle, and a sliding and spring-pressed hammer in the tubular handle and having a member projecting through the slot of the handle to permit the hammer to be moved against the tension of the spring.

5. In a saw-set, a head, a handle secured to the head and provided with two chambers one in the rear of the other the forward

chamber being open at the top and the rear one provided with a longitudinal slot, an anvil carried by the head, a slotted jaw also carried by the head, opposite the anvil, a spring-pressed setting-bar mounted in the forward chamber with its ends projecting through the end walls of the chamber, a hammer in the rear chamber of the handle and provided with a pin projecting through the slot of the said chamber, and a spring coiled on the rod between one end of the chamber and the said pin.

In testimony whereof I have signed my name to this specification in the presence of two subscribing witnesses.

CHARLES DIENER.
